Primary Examiner — Ian Simmons*Assistant Examiner* — Richelle G Shelton(74) Attorney, Agent, or Firm — Sheridan Ross P.C.(57) CLAIM

The ornamental design for a display screen with graphical user interface, as shown and described.

DESCRIPTION

The single FIGURE is a front view of a display screen with graphical user interface.

The broken line showing of the display screen illustrates the environment of the claimed design and forms no part thereof.

1 Claim, 1 Drawing Sheet(56)
